G.W.Harley,

UNITED STATES PATENT OFFICE

GEORGE W. HARLEY, OF COLLINGSWOOD, NEW JERSEY

GUIDE AND PATTERN STRIP AND ANCHOR THEREFOR

Application filed October 20, 1927. Serial No. 227,563.

The present invention consists of a guide and pattern strip and anchor therefor used in plastic work, especially in laying terrazzo or similar flooring.

5 An object of the invention is to provide an anchor which is separate from the strip and is insertable through the latter to provide lugs on opposite sides of the strip.

A further object of the invention is to provide anchoring plates which may be engaged with the strips in a facile manner and are secured thereto to prevent accidental displacement of the plates.

Coordinate objects of the invention are to provide anchors which are engageable through the strips at any point intermediate the longitudinal edges of the latter to prevent lateral displacement of the strips; to provide anchors of this character which are engaged with the strips in such a manner as to provide gauges to automatically regulate the depth of penetration of the strip into the screed coat and correspondingly to define the thickness of the terrazzo which is laid on the screed coat; to provide anchoring plates which may be quickly engaged with the strips and are secured thereto to prevent relative movement of the plates and strips; to provide anchoring plates which not only serve as anchors and gauges in the manner set out above, but which may likewise be used to unite adjacent strips together in order to eliminate relative movement of the adjacent strips; and to provide anchoring plates or gauges which are relatively flat and are separate from the strips which permits the strips and anchors to be transported separately, the construction of the anchors being such as to permit assemblage of the same with the strips on the job.

Other objects of the invention will be apparent from the following description of the present preferred forms of the invention, taken in connection with the accompanying drawings, wherein

Figure 1 is a fragmentary top plan view of pattern and guide strips constructed in accordance with the present invention, illustrating the application of certain forms of my improved anchoring plates thereto;

Figure 2 is a transverse sectional view of the same;

Figure 3 is a top plan view of a bifurcated anchor plate illustrating the manner of engaging the same with two adjacent pattern strips arranged in end to end relation;

Figure 4 is a side elevational view of a modified form of anchor plate, illustrating its application on a strip;

Figure 5 is a perspective view of the same;

Figure 6 is a top plan view of another modified form of anchor plate, illustrating its application on a strip;

Figure 7 is an end elevational view of the same; and,

Figure 8 is a fragmentary perspective view of a pattern strip, adapted for the reception of a bifurcated anchor plate.

In the use of guide and pattern strips, it is customary to first pour a plastic composition, known as the screed coat or layer, upon a solid foundation and when the consistency of the screed coat has changed into a semi-plastic condition, the strips are placed in a vertical position and one of the longitudinal edges thereof urged into the screed coat. It is customary in the art to strike out or otherwise integrally form anchors on the strips which tend to stabilize the latter and, in addition, limit the extent of penetration of the strip in the screed coat. The top layer, such as terrazzo, or the like, is then laid on the screed coat above the anchors, the top of the terrazzo being flush with the upper marginal edges of the strips. The strips in this way tend to unite the screed coat with the upper mosaic coat in a manner well-known in the art. It is the purport of the present invention to make the anchors separate to permit sliding the same transversely through the strips in order to provide anchoring elements at directly opposite points on the strip, to eliminate the possibility of lateral tilting of the strips. Moreover, the anchors are relatively narrow to reduce the surface area to be impinged by the plastic material to eliminate the possibility of distorting the strips. I have herein illustrated different forms of anchor plates which serve not only to anchor the strips, but likewise to act as height gauges,

100

some of the forms of which are capable of uniting the strips together.

In the drawings, strips 9 are shown which are preferably made of brass and are of standard construction, except for the provision therein of openings generally designated 10. The openings may be single or double, depending upon the configuration of the plate used, as more fully hereinafter described. Moreover, the openings may be arranged along the longitudinal center of the strip or may be offset from the longitudinal center in order to increase or decrease the thickness of the upper mosaic layer. The openings are elongated, extending horizontally to correspondingly position the plates inserted therethrough so that the upper and lower faces of the plates will be parallel to the longitudinal edges of the strips.

The preferred form of plate, as illustrated to advantage in Figure 3, consists of an oblong body 11, one end of which is bifurcated to provide furcations 12. The furcations are adapted for use in a variety of ways. For instance, the furcations may be inserted through twin slots or openings such as shown in the strip illustrated in Figure 8 of the drawings. When used in this way the opposite ends of the plate on each side of the strip are equi-distant from the opposite faces of the latter, to provide oppositely disposed lugs, the lower faces of which are adapted for impingement against the upper surface of the screed coat, while the upper faces thereof are adapted to receive the outer or mosaic coat thereon. The bight between the furcations is adapted to receive the plastic material therein so as to lock the anchor plate from displacement. The bifurcated plate may also, as illustrated in Figures 1 and 2 of the drawings, be used to connect adjacent right-angular strips together. When used in this way, the furcations 12 are inserted through twin slots formed in one of the strips and will straddle the terminal of the adjacent strip. The adjacent strip fits in the bight between the furcations and abuts the right-angular strip which carries the anchor plate. The bifurcated plate may also be used to connect adjacent guide strips which are arranged in end to end relation, as shown in Figure 3 of the drawings. When used in this manner, the furcations 12 of the plate are engageable through complementary openings formed in the adjacent ends of the strips to thereby effect a locking engagement of the latter. When the anchor plate is used in this manner, the plastic material is permitted to gravitate through the bight between the furcations to lock the anchor plate from displacement. It is desired to equip the plate with means by which it is secured to the strip or strips and it has been found desirable, for this purpose, to equip the plate with protuberances which frictionally engage the walls of the openings

or slots in the strips through which the plate passes. The protuberances used on the plate 11 consist of longitudinally extending ribs 13 which are pressed outwardly through one face of the plate. Preferably the protuberances extend for an appreciable distance midway the ends of the plate, to extend completely across the slots or openings in the strips in which the anchor plates are engaged. The protuberances positively retain the anchor plate in the guide strip or strips from displacement.

In Figure 1 another form of anchoring plate is indicated at 14, this also being of oblong shape and being provided with a protuberance 15 extending through its longitudinal center, which serves in the same capacity as the protuberances 13. The plate 14 is adapted for engagement through a complementary slot or opening formed in the strip and when in engagement, the opposite ends thereof are equi-distant from the opposite sides of the strip and at right angles to the latter. As many of the plates 14 as desired may be used, this construction of anchor plate being preferable at points intermediate the ends of the guide strips.

In Figures 4 and 5 of the drawings, a further modification of anchor plate is shown, as indicated at 16. This plate is also of oblong configuration and is provided in the center thereof with a struck-out tongue 17 which is adapted for impingement against one side of the guide strip to limit the extent of movement of the anchor plate through the latter. This form of plate is provided with longitudinally extending protuberances 18, formed on opposite sides of the tongue 17. The plate 16 is adapted for insertion horizontally through the guide strip and is used in the same manner as the plates 11 and 14. The plastic material is permitted to pass through the opening 19 formed by striking out the tongue 17 to further lock the plate from displacement. In the form of invention shown in Figures 6 and 7, a plate designated 20, is employed, which is equipped with a pair of tongues 21, used in the same manner as the tongue 17. In addition, the plate 20 is equipped with a stud or protuberance 22, which co-acts with the tongue 21 to prevent longitudinal movement of the plate through the guide strip.

In using border guide strips, sufficient space is not always provided to accommodate the anchor plates and, consequently, in use of any of the present forms of anchors, a portion of one end thereof can be removed without in any way mitigating the effectiveness of the balance of the anchor. The anchor plates may be made of any desired material, preferably, however, a metal. The anchor plates are so small that scrap metal may be advantageously used in the construction of the

anchor plates in order to reduce cost to an absolute minimum.

Although I have described herein the preferred forms of my invention, it is, nevertheless, to be understood that various changes may be employed in making up the anchor plates and associating them with the guide and pattern strips in harmony with the teaching of the present invention. It is of the essence of importance, however, that the guide strips be provided with slots or openings which are adapted to receive anchor plates extending transversely therethrough in a horizontal plane, and so constructed that they will be locked from displacement in the strips. The bifurcated anchor plate constructed in accordance with this invention not only serves in the capacity of an anchor plate and gauge, but when used as set out herein, it serves to positively lock adjacent strips together and prevent relative movement thereof, which has been a source of annoyance to workmen in laying floors of this kind heretofore.

What is claimed is:

- 25 1. A pattern strip and anchor therefor, including a strip provided with openings therethrough intermediate its longitudinal edges, and a flat anchor plate engageable in each of said openings.
- 30 2. A pattern strip and anchor therefor, including a strip provided with openings therethrough, and a flat anchor plate arranged through each opening, the faces of which are parallel to the longitudinal edges of the strip.
- 35 3. A pattern strip and anchor therefor, including a strip provided with openings therethrough, anchor plates detachably engaged through said openings and equipped with protuberances co-acting with the strip to prevent relative movement of the plates and strip.
- 40 4. A pattern strip and anchor therefor, including pattern strips arranged in end to end relation and provided with openings in the adjacent ends thereof, and an anchor plate engageable through said openings.
- 45 5. A pattern strip and anchor therefor, including guide strips arranged at right angles to each other, and an anchor plate extending through one of the strips and embracing the terminal of an adjacent right angular strip to retain said strips in position.
- 53 6. Means for use in making plastic flooring, including strips, and relatively flat oblong plates engageable through said strips and arranged to lie in a horizontal plane.
- 60 7. A division device for terrazzo flooring including a strip, and an anchor plate engageable through said strip and equipped with means to limit the extent of its movement through the strip.
- 67 8. Means for use in making plastic flooring including pattern strips arranged in end

to end relation and at right angles to one another, and anchor plates engaged with the strips to hold the latter together, said plates being flat to receive the plastic material for anchoring the strips.

9. A terrazzo strip or analogous structure comprising a main strip having slots, and separate anchor pieces extending through the slots and projecting at opposite sides of the main strip, the anchor pieces having integral formations engaging opposite faces of the main strip and retaining them in position.

10. A terrazzo strip or analogous structure comprising a main flat sheet metal strip having spaced slots therethrough, and separate anchor pieces of generally flat sheet metal extending through the slots and projecting at opposite sides of the main strip, the anchor pieces having integral formations engaging opposite faces of the main strip and retaining them in position.
